HAIR CURLER

Mildred Pavlot, Pittsburgh, Pa.; now by change
of name Mildred P. Patrina

Application May 18, 1951, Serial No. 226,984

6 Claims. (Cl. 132—41)

1

The present invention relates to a hair waver and curler and it consists in the combination, construction and arrangement of parts herein described and claimed.

Generally there is provided a novel hair waver and curler which comprises a main frame and a pair of successively smaller frames which are consecutively hinged and finally a spindle which is hinged to the smallest of the three frames. The frames are substantially rectangular in shape and may be extended so that hair may be wound one-third of the way from the tip ends thereof to the head upon the spindle and thereafter the spindle turned into and latched to the smallest of the three frames whereupon another one-third of the hair may be wound in an opposite direction thereon after which it may be latched within the intermediate frame and the remainder of the hair wound again in an opposite direction upon the intermediate frame whereupon the same may be latched in the biggest or outer frame member adjacent the head of the user. The device is of such character that it will efficiently wave and curl hair even though only water is applied thereto prior to the application of this device to the hair.

It is accordingly an object of the invention to provide a novel hair waver and curler.

Another object of the invention is to provide a compact device of the character set forth which is simple in construction, inexpensive to manufacture and yet effective and efficient in use.

A further object of the invention is the provision of a device of the character set forth which is unitary in character.

Other and further objects of the invention will become apparent from a reading of the following specification taken in conjunction with the drawing, in which:

Figure 1 is an elevational view of an embodiment of the invention shown in closed condition.

Figure 2 is a reduced view similar to Figure 1 but showing the device in its extended position.

Figure 3 is a series of related schematic views illustrating the manner of use of the device, and

Figure 4 is a fragmentary plan view of a modified form of frame member.

Referring more particularly to the drawing, there is shown therein a hair waver and curler comprising an outer substantially rectangular frame 10 to one side of which is pivotally connected, as indicated at 11, an intermediate frame 12 likewise rectangular in shape and to whose other end is pivotally connected, as indicated at 13 an inner frame 14, likewise rectangular in

2

shape and smaller than the frame member 12. To the outer end of the frame member 14 there is pivotally connected, as indicated at 15, a spindle 16.

5 The frame member 14 is provided with an undercut recess 17 for latching the free end of the spindle 16 therein. The frame member 12 is provided with a recess 18 for latching the frame member 14 therein and the frame member 10 is provided with a recess 19 for latching the frame member 12 therein. The sides of the members 16, 14, 12 and 10 are as shown in flat construction but may be corrugated, as indicated at 12a, 14a and 16a, in Figure 4 of the drawing.

10 In operation, it will be apparent that strands of hair which are indicated by the line 21 in Figure 3 may be wrapped with this device toward the head from the outer ends of such strands as indicated by the arrow 22 forming a

15 part of Figure 3. In such treatment, one-third of the strands 21 are first wound clockwise upon the spindle 16, as indicated by the arrow 23 whereupon the spindle 16 is latched in the recess 17 within the frame member 14. After this is

20 accomplished, the next one-third of the strands 21 are wound in a counterclockwise direction, as indicated by the arrow 24 upon the frame member 14 after which the frame member 14 is latched within the frame member 12. Next the

25 last remaining one-third of the strands of hair 21 are wound in a clockwise direction, as indicated by the arrow 25, upon the frame member 12 after which the frame member 12 is latched in the undercut at 19 within the outer frame

30 member 10 and the device will now be next to the scalp of the user where it may remain for a sufficient length of time to properly wave and curl the hair.

35 While but one form of the invention has been shown and described herein, it will be readily apparent to those skilled in the art that many minor modifications may be made without departing from the spirit of the invention or the scope of the appended claims.

40 45 What is claimed is:

1. A device of the character described comprising an outer frame, an intermediate frame pivoted to said outer frame, an inner frame pivoted to said intermediate frame, and a spindle pivoted to said inner frame.

50 55 2. A device of the character described comprising an outer frame, an intermediate frame pivoted to said outer frame, an inner frame pivoted to said intermediate frame, a spindle pivoted to said inner frame, and means formed

on the members for latching each of said spindles and inner and intermediate frames to its neighboring frame at a point opposite the pivot position.

3. A device of the character described comprising an outer frame, an intermediate frame pivoted to an end of said outer frame, an inner frame pivoted to the free end of said intermediate frame, a spindle pivoted to the free ends of said inner frame, and means formed on the members for releasably latching each of said spindles and inner and intermediate frames to its neighboring frame at a point opposite the pivot position, all of said members being corrugated between their ends.

4. A hair-curling device that comprises a frame of generally elongated loop form, a second and smaller loop-like frame pivoted at one end to an end of the other frame, and a spindle pivoted at one end to the free end of the second-named frame, the frame members and the spindle being foldable relative to one another.

5. A hair-curling device that comprises a frame of generally elongated loop form, a second and

smaller loop-like frame pivoted at one end to an end of the other frame, and a spindle pivoted at one end to the free end of the second-named frame, the frame members and the spindle being foldable into interfitting relation on a common plane.

6. A hair-curling device that comprises a frame of generally elongated loop form, a second and smaller loop-like frame pivoted at one end to an end of the other frame, and a spindle pivoted at one end to the free end of the second-named frame, the frame members and the spindle being foldable relative to one another and being corrugated transversely of their longitudinal axes.

MILDRED PAVLOT.
